UNITED STATES PATENT OFFICE.

YOSHIO MATSUMURA, OF TOKYO, JAPAN.

DIVING APPARATUS.

1,375,715.

Specification of Letters Patent. Patented Apr. 26, 1921.

Application filed August 14, 1918. Serial No. 249,890.

To all whom it may concern:

Be it known that I, YOSHIO MATSUMURA, a subject of the Emperor of Japan, and a resident of No. 624 Horikiri, Minami-kat-
5 sushika-Gun, Tokyo, Empire of Japan, have invented new and useful Improvements in Diving Apparatus, of which the following is a specification.

This invention relates to improvements in
10 diving apparatus for use in working among wrecks or other like subaqueous objects, and comprises a hermetically closed casing hereinafter called a shell, containing necessary machines, implements and other appliances
15 including air supplying and water exhausting means, so that the apparatus can be lowered from a vessel and held at the level adjacent to the wreck or other submerged objects, to enable a diver to make his exit
20 from a room which is specially provided for him in one part of the said casing to work at the wreck or other submerged objects. The invention also comprises means whereby air, approximately at atmospheric
25 pressure, can be supplied to the diver, regardless of the depth of water.

In order that this invention may be clearly understood and more readily carried into practice, reference may be had to the
30 appended drawings, in which:—

Figure 1 is a side elevation of the shell.

Fig. 2 is a vertical central sectional view of the same.

Fig. 3 is a transverse sectional view of the
35 same on a plane intersecting the maneuvering chamber.

Fig. 4 is a transverse sectional plan view of the power chamber.

Fig. 5 is a transverse sectional plan view
40 of the machine chamber.

Fig. 6 is a detail view showing the opening and closing mechanism of the door.

Fig. 7 is a side elevation of the air pump, partly broken away to expose the interior.

Fig. 8 is a plan thereof.

Fig. 9 is a transverse sectional plan of the purifier.

Fig. 10 is a longitudinal section of the purifier.

50 In the drawings illustrating the construction and application of the invention, the numeral 1 designates a cylindrical casing or shell preferably made of plate iron or other like strong material sufficient to withstand great water pressure. Partitioned by two

floorings A, A', the shell is internally separated into three compartments, viz., maneuvering chamber 2, power chamber 3, and machine chamber 4, respectively.

In the lowermost chamber 4, an inner wall 60
6 spaced from the outer wall of the shell is provided so as to form an annularly inclosed space 7 thereof as shown in Figs. 2 and 5. A portion of this machine chamber 4 is further partitioned by longitudinal wall B, 65 thereby providing a room 5 for the diver to occupy and from which he can pass out to work through the door-way which is provided in the inner and outer walls of the shell, as at 9. 70

In the door-way 9 slidably fits a rectangular curved door 8 which is provided with an opening 9' corresponding to the size of the door-way 9, and which moves in the said annular space 7, thereby causing the door-way 9 to be opened when the door 8 is moved to the position in which no portion of the opening 9' is covered by both inner and outer walls of the shell, but closed when the door 8 is moved to the position in which the opening 9' is covered by both the inner and outer walls of the shell. 75

The opening and closing movement may be imparted to the door 8 by any suitable means but I have shown by way of example 85 in Fig. 6 one most simple and convenient means which consists in providing at each of the four corners of the door 8 a laterally extending rack 10 adapted to engage a corresponding pinion 11 turning on the axis 90 connecting with the shaft in the power chamber as will appear later. To facilitate the movement the guideway 12 with which the sliding edges of the curved door 8 engage, may be provided with anti-friction rollers 95 as at 13.

Secured to the under side of the base plate C of the shell is a flaring bowl-like member 13 adapted to receive the water which may enter the diver's room and other parts of 100 the shell in the manner hereinafter described, said member forming a bilge water chamber 14. The said member 13 has a central recessed portion 15 in which upper and lower contact carriers each consisting 105 of an electrically insulated hollow cylinder 16, and an interposed compression 17, are disposed. Each cylinder is provided at its inner surface with a contact piece 18, the contacting and detaching action of which 110

permits the circuit through the conductor 19 to make or break. The conductor 19 which is shown passing through the interior of the shell is led from the top end thereof 5 into the vessel, not shown.

To the lower contact carrier 16 is fastened one end of the cable 20, the other end of which cable is attached to a sinker 21 of any desired form, but sufficiently heavy to 10 overcome the tension of the spring 17, so that in the sinking movement of the shell the two contact pieces 18 are separated from each other. When the sinker 21 reaches the sea bottom the cable slackens 15 and the spring 17 brings the pieces 18 into mutual contact, thereby completing the electric circuit and causing the bell or gong to ring and hence notify the man in the chamber 2 of the approaching to the sea 20 bottom, and avoiding the danger of the shell suddenly striking on the sea bottom. The time of warning may be varied by adjusting the length of the cable. Preferably the lower opening of the recess 15 may 25 be closed by a perforated plate, not shown, so that the water entered into the recess in the upward movement of the lower contact carrier 16 will be expelled through said perforated plate in the downward movement 30 of the lower contact carrier 16.

Conveniently, the upper end of the shell 1 may be likewise provided with similar bowl-like member 13' and may be provided with a hole for leading the circuit cable 19 35 therethrough. D is a manhole permitting the operator to go in and out of the maneuvering chamber. E is a water tight cover fitted thereon.

A protecting means, preferably in the 40 form of ring fenders 22, is provided, encircling the upper and lower ends of the shell, said fenders being supported by a plurality of radiating arms 22' extending from the outer periphery of the shell, as shown in 45 Fig. 5. The fenders are further mounted at several points with an additional protecting means preferably in form of an ordinary buffer 23 as shown in Fig. 4.

Formed upon and practically covering 50 the entire upper surface of the lower fender 22 is a platform H with a suitable railing 24 to provide a safe foothold for the diver at work, as shown in Figs. 1 and 5. At 27 and 27' are shown the search light 55 and peep window respectively, each of which is provided with a glass protector of usual form.

The shell may be lowered from the vessel by means of a cable 26 which is coupled to 60 the cables 25 which suspend the shell.

The chamber 2 contains a switch-board 28 equipped with usual devices such as ammeter 29, voltameter 30, pilot lamp 31, and two switches 32 and 32' respectively. The 65 switch 32 is designed to control the opera-

tion of the air pump as will appear later. The other switch 32' is adapted to control the movement of the door of the diver's room, besides controlling the operation of the water pump 49 and vacuum pump 50, 70 as will appear later.

Although not shown in the drawings, the following instruments may be installed upon the wall of the chamber adjacent to the switch-board, namely, indicator to indicate the position of the door 8, pressure gage to ascertain the water pressure both inside and outside of the diver's room, alarm bell to announce the approaching of the sea bottom, thermometer, hygrometer 80 vacuum gage, draft gage to ascertain the pressure of the air draft for the diver, manometer to indicate the residual pressure of the compressed air tank, oxygen gage for air purifier, acetylene gas meter, etc., all 85 arranged in appropriate order and communicating with appropriate tanks. The numeral 34 indicates a telephone to facilitate communication between the operator and diver and the vessel. 90

Located below the gages and meters above mentioned, preferably a transformer and electric heater may be arranged, so that the air in the chamber may be kept at and warmed to good working temperature. 95

Suitably spaced from these meters and gages there is placed upon the floor of the maneuvering chamber a chair 35, preferably of rotatable type and in practice provided with a belt for the support of the operator sitting thereon. The chair may be further equipped with a suitable oxygen inhaler which communicates through the medium of the pipe 36 with the oxygen tank placed in the machine chamber 4, thus 100 enabling the operator sitting on the chair 35 to inhale it at will whenever the oxygen in the chamber becomes deficient. Near the chair is a controller 37 which governs the operation of the motor 41 installed in the power chamber 3. An additional supporting means for retaining the body of the operator enabling him to operate the instruments mounted upon the opposite wall, comprises, as shown in Figs. 2 and 3, a 115 semi-circular arm F attached to one end of the horizontally disposed preferably telescopically adjustable shank 38, the other end of which shank is pivoted to the upper end of the vertical shaft G which extends to 120 a suitable height from the floor of the chamber 2. T is the supporting belt attached to the end of the arm F. 39 is an air purifying apparatus. 40 is a hand wheel governing the opening and closing 125 of the bilge water valve 70' which is provided in the base plate C of the floor of the machine chamber 4, Fig. 2.

As shown in Fig. 4, the power chamber 3 contains a motor 41 adapted to be electri- 130

cally driven through the manipulation of the switch 32 and controller 37. The motor transmits by belt motion to the main shaft 42 horizontally disposed upon the floor of the chamber, a portion of which shaft passes through the bore of the sleeve shaft 42'. As this latter shaft is provided at one end with a pulley 43' and as the main shaft 42 is likewise provided with a pulley 43, it is obvious that by the provision of a hand or electrically operable belt-shifter, the motion transmitted from the motor onto the pulley 43 can be shifted to the pulley 43', and vice versa. It is also obvious that by setting the pulley 43 in motion the main shaft 42 is rotated while the pulley 43' rotates the sleeve shaft 42'. This shaft 42' is used to drive both vacuum pump 50 and bilge pump 49, while the main shaft is used to operate the door 8 of the diver's room, motion being transmitted from the shaft 42 to the shafts 44, 44' by means of a belt K mounted upon the respective pulleys L, secured to each end of the main shaft. It will be observed that as the shaft 44' is geared directly with the shaft which carries the pinion 11 while the other shaft 44 is geared indirectly through the medium of an intermediate shaft 44'' with the pinion 11', it is possible to rotate both pinions 11 and 11' in opposite directions so as to cause the door 8 to move in either direction, to open or closed position.

At 41' is represented another motor adapted to drive the air pump. This motor is provided to prevent the working of the air pump being discontinued during the operation of the door.

The machine chamber 4 contains, as shown conventionally in Fig. 5, acetylene tank 45, oxygen tank 46 for working tools, oxygen tank 47 for purifying the air, air pump 48, bilge pump 49, vacuum pump 50, vacuum tank 51, compressed air tank 52, purifier 53.

The acetylene tank 45 and oxygen tank 46, respectively, are connected by pipes 54 and 54', with the working implements, not shown. The purifier 53 is connected with the oxygen tank 47 by means of a pipe 55. The purifier is further connected with the vacuum tank 51 by means of a pipe 55'. The purifier is shown still further connected with the compressed air tank 52 by means of a pipe 56.

The purifier is shown still further connected by means of two pipes 57 with the air pump 48 which in turn connects also by means of two other pipes 57 with the diver's suit so that the air is enabled to be drawn and supplied from the purifier to the diver, and the vitiated air passed back to the purifier.

The bilge pump 49 is connected by means of a pipe 58 with the bilge water chamber

14. The diver's room is connected by means of a pipe 59 with the compressed air tank 52.

The air pump 48 which differs in construction from the ordinary device is illustrated in Figs. 7 and 8 wherein each of two cylinders juxtaposedly arranged in vertical position are internally divided by means of a central partition 61 into two chambers 64, 64', respectively, adapted to receive therein a valve loaded piston 62, 62', both carried by the same spindle 63. The action is such that while the vitiated air is drawn into one chamber the clean air received by the other chamber is drawn out therefrom and supplied to the diver, but in the next stage of stroke the vitiated air received by the first named chamber is drawn out therefrom into the purifier and at this instant the last named chamber receives the clean air. This motion of the pump being alternate and simultaneous with respect to two cylinders affords the supply of clean air to the diver continuously.

The purifier used in the present invention is illustrated in Figs. 9 and 10, comprising a hollow casing in which are arranged superimposedly two drawers, as at 66. In the lower drawer is installed an electric heater of any appropriate form. The upper drawer which has a perforated bottom, comprises a plurality of wire nettings 67 arranged in spaced order one upon the other, and each of which nettings is filled with sodium peroxid with the exception of the uppermost netting upon which is placed raw lime to absorb moisture. Located below the upper drawer are two pipes 56 and 68, respectively. The pipe 56 which connects the compressed air tank 52 is used to furnish fresh air to the purifier for use by the diver. The pipe 68 which connects to the nose of the diver is used to draw into the purifier the vitiated air exhaled by the diver, which vitiated air after being filtered and clarified through the sodium peroxid is returned to the diver by way of the supply pipe 69. The pipe 55 which connects the oxygen tank 47 is used to furnish oxygen into the purifier.

Referring again to Fig. 2, a bilge water valve 70' is provided in the base plate C of the machine chamber 4, the spindle 70 of which valve is shown elongated to pass upwardly through two floors A, B, to be manipulated by the operator in the maneuvering chamber 1. To facilitate repairing or in other emergencies, so that the operator may be able to gain access to the machines, a tunnel tube 71 internally equipped with a suitable step ladder 73 is provided. At 72, Fig. 3, is shown a cover to be placed over the tunnel opening. Upon the floor 76 of the diver's room 5 is provided an exhaust valve 75 which is operable by the foot of

the diver sitting upon the rotatable chair 74. The pressing and releasing action of the foot enables the valve to be opened or closed so that the water filled in the room 5 before 5 the diver makes his exit will be emptied into the bilge water chamber 14 upon his return to the room, the door 8 at this moment being closed after him as he enters the room. While exhausting the water out of 10 the diver's room an adequate quantity of water should be supplied from the compressed air tank 52 into the room, to protect the diver from the effects of the sudden change of the pressure in the room. 15 In practice, the apparatus is thoroughly examined on board vessel. After ascertaining that all parts are in order the operator enters through the opening D into the maneuvering chamber, while the diver, properly armored and equipped, enters his room 5. The opening D and the door 8 being then closed and the machines being set in motion, the shell is put overboard and lowered by means of the cable 26 into the place 20 where the wreck or other object to be operated upon is located. The door is then opened and the outside water is caused to enter into the room to equalize the inside pressure when the diver makes his exit to 25 engage at work. Upon the diver's return to the room the door is closed and the water is drawn therefrom into the bilge water chamber 14.

My improved apparatus supplies the diver 35 with air at approximately atmospheric pressure and when the apparatus is used in connection with an armor of my invention for which I am about to file application for Letters Patent of the United States, enables 40 the diver to work without inconvenience in water at great depth.

The provision of the purifier permits not only the reduction of the compressed air but at the same time facilitates the circula-

tion of clean warmed air between the interior of the shell and the diver engaging at work outside of the shell. 45

What I claim is:

1. In diving apparatus, a shell having an outer wall provided with a door opening 50 and an inner wall spaced from the outer wall and also having a door opening opposite that of the outer wall, a sliding door arranged in the space between the inner and outer shells and having an opening adapted 55 to register with the first named openings when said door is in one position, and means to operate said door.

2. In diving apparatus, a shell having an outer wall provided with a door opening 60 and an inner wall spaced from the outer wall and also having a door opening opposite that of the outer wall, a sliding door arranged in the space between the inner and outer shells and having an opening adapted 65 to register with the first named openings when said door is in one position, and also having racks, and operating means for the door, including gears which engage said racks. 70

3. In diving apparatus, a shell having an outer wall provided with a door opening and an inner wall spaced from the outer wall and also having a door opening opposite that of the outer wall, a sliding door 75 arranged in the space between the inner and outer shells and having an opening adapted to register with the first named openings when said door is in one position, and also having racks, and operating means for the door, including gears which engage said racks and a motor.

In testimony whereof I affix my signature in presence of two witnesses.

YOSHIO MATSUMURA.
